(57) **CLAIM**

The ornamental design for a pull up exerciser, as shown and described.

DESCRIPTION

FIG. 1 is a front and top perspective view of a pull up exerciser, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged perspective view of detail "9" identified in FIG. 1; and,

FIG. 10 is an enlarged perspective view of detail "10" identified in FIG. 1.

The dashed lines in the figures illustrate portions of the pull up exerciser that form no part of the claimed design. The dash dot dash lines in FIGS. 1, 9 and 10 depict the bounds of the enlarged views and form no part of the claimed design.

1 Claim, 10 Drawing Sheets
